FLOW CONTROL HEAD

Application filed December 11, 1929. Serial No. 413,384.

This invention has to do with apparatus for controlling flow from a well, such as an oil-well. The general objects and corresponding accomplishments of the invention will be best understood from a short description of the conditions with which the invention is designed to cope.

When a flowing well is "brought in" after the drilling operations have been completed and the well pipe set, it is necessary to hold down the gas and oil pressures in order to keep the well from blowing out uncontrollably. If those pressures are freely released, the gas pressure, which is the impelling force that brings the oil into the well, may be freed so quickly that gas will flow into and out of the well without bringing any substantial amount of oil with it; and when the gas pressure subsides comparatively little oil will thereafter be brought into the well. For that reason it is common to fill the well with some heavy fluid such as heavy mud, so as to provide a column in the well of sufficient weight to hold down the pressure.

25 The tubing or other flow pipe may then be installed in the well; and then by use of a swab the mud column is moved up out of the flow pipe until the column height is reduced so that the pressures will move it upwardly. 30 The swab is run up quickly, and then the well begins to flow. A typical swab is simply a plunger-like member having a leather cup or rubber washer in close contact with the wall of the pipe being swabbed, and when this 35 swab is raised with a hoist line it moves the column of mud upwardly and out of the pipe.

It is frequently necessary to raise or otherwise adjust the tubing or flow pipe after it has been installed. The well pipe or casing is usually provided with a screen or perforated pipe through which the oil enters the well. A certain amount of silt is carried in the oil and settles into the bottom of the well, thus eventually clogging and filling the lower 45 portions of the well and the screen openings. When this occurs it is frequently necessary to raise the tubing or flow pipe to a point above the accumulated silt so as to keep the flow pipe open. However, with present day 50 equipment, it is impossible to elevate the tub-

ing to raise its intake to a higher level, or in any manner to adjust the tubing, and still control the flow therethrough. This is for the reason that the joints at the top of the tubing must be broken before vertical movement of the string, and once the joint is broken control of the flow is lost.

As the practice is now it is necessary, in order to adjust the tubing, to fill the well again with heavy mud to hold down the pressure while the tubing is being raised. Such application of heavy mud to the well is very likely to "kill" the well by reason of the mud backing up into the oil sands and clogging up the screening openings. In fact, there have been many instances in which good wells have been rendered virtually worthless; and in many cases the subsequent production is cut down by amounts up to fifty per cent. The operation is therefore one which oil operators hesitate to use; and often the raising or other adjustment of the tubing is put off until the well is so silted up that tubing adjustment then avails nothing.

The object of this invention is to provide an apparatus by which pressures and flow may be controlled when it is desirable or necessary to adjust the position of the tool when, otherwise, the upper end of the tubing would necessarily be open.

I will describe briefly in a typical form my apparatus, which involves a fitting applicable to the upper end of the tubing string in the well, which fitting provides for the addition or taking away of tubing lengths, as may be required in the operation of adjusting the tubing. Valve controls are associated with this fitting, operable in such a manner as to shut off the upper end of the tubing string completely, or to allow controlled flow from the tubing. One of these valve controls is adapted to shut off or open the tubing-receiving bore which extends through the fitting; and the length of tubing which is being put on to or taken away from the string is held in a cap member which, when in position, makes a fluid tight joint between the length of tubing and the fitting itself. The upper end of the tubing length being capped during the operation, the valve

which controls the tubing bore can be opened and the extra length of tubing threaded down into the joint at the upper end of the tubing string.

- 8 The tubing which I speak of here may be any flow pipe through which the oil flows from a well; I speak of tubing merely because such pipe is so termed. It will be recognized, however, that the specific nature of the pipe, and the other uses to which it may be put (for instance to accommodate a deep well pump) will not change the nature of operation nor the applicability of my invention to accomplish its stated purposes.
- 12 The invention itself, further objects and accomplishments, will be best understood from the following detailed description of a typical and illustrative embodiment of the invention, reference being had to the accompanying drawings in which

16 Figure 1 is an elevational view showing the general assembly of my devices applied in one form to a well.

20 Fig. 2 is a similar view showing a modified application.

Fig. 3 is an enlarged vertical section of the upper part of Figure 1.

Fig. 4 is a horizontal cross section on line 4-4 of Figure 3.

24 Fig. 5 is a horizontal section on line 5-5 of Figure 3.

Fig. 6 is an enlarged vertical detail section of certain parts of Figure 2.

28 In the drawings let 10 designate the casing or well pipe and 11 the string of flow pipe or tubing standing in the well. In Figures 1, 3, 4, and 5 I illustrate the application of my apparatus to tubing of the ordinary collar jointed type, with the fitting F adapted to take that type of tubing. Figures 2 and 32 show a modification adapted to take flush joint tubing as will be hereinafter described.

36 During the operation of raising or lowering the string of tubing, the string will be supported by any suitable supporting means, typified by the slips E shown in the drawings. Any supporting means may be used. When such a string of tubing is first installed in the well, some suitable plug or packing means is placed about the tubing at a suitable distance below the top. For instance I show a packing cup 12 mounted on the tubing string and adapted to prevent upward flow of fluids through the casing around the tubing. This packing cup will be installed on the tubing at a distance below the top somewhat greater than the vertical distance it is anticipated the tubing may afterwards have to be adjusted.

40 Referring now more particularly to Figure 3, fitting F is seen to have what I will call a tubing bore 15 enlarged at its lower end as at 16 to take the tubing collar 17. The walls of bore 16 may be provided with circumferential packing 18 so that a fluid tight joint may be

made with the tubing or tubing collar; and the whole fitting is held securely to the upper end of the tubing string by means of clamping dies 19 set up by set screws 20.

44 The upper part 15 of the tubing bore is of such a size as to freely take the upper tubing length 11a; and just above the collar receiving bore 16 there is a horizontally sliding gate valve 21 operating by a screw 22 with a hand wheel 23 on its outer end. This gate valve 21 can slide horizontally in the rectangular recess 24 formed in the fitting F, the recess 24 forming an enclosed guiding way for the valve. The valve may be put either in the position shown in Figures 3 and 4, to close off the tubing bore above the upper end of tubing string 11, or the valve may be withdrawn toward the left so as completely to open the tubing bore.

48 At the side of the fitting opposite the valve wheel I provide an outlet 25, controlled by a valve 26, which valve controlled outlet is always in communication with the tubing bore below the gate valve 21.

52 In order to facilitate placement of the fitting upon a tubing, the fitting is formed in two parts hinged together at the hinge 27, and the two parts may be securely clamped together around the tubing by means of the clamp 28, best shown in Figure 4. The details of this clamp need not be described minutely, except to say that a pressure screw or screws 29 are used so that the two halves of the fitting may be tightly clamped together. It will, of course, be understood, and this is also true of the two-part cap C hereinafter described, that the packing 18 is likewise constructed or formed in halves so that it will part on the plane of separation of the fitting halves. This plane of separation is longitudinal of, and substantially diametrical of, the pipe-receiving bore. The two hinged halves are generally designated in the drawings by the numerals 30 and 31, the half 31 being that in which gate valve 21 is housed. In order to house this gate valve, that half 31 is made in two parts, one of which is a cover part 32. The outline of this cover part is shown partially in dotted lines in Figure 3. It is held down on the lower part of half 31 by flange bolts shown at 34 in Figure 4.

56 It is to be noted that the fitting, and also the cap C hereinafter to be described, are made in halves primarily to facilitate placement about the tubing without having to pass the fitting and cap over the tubing end. However, the clamp 28, and the corresponding clamp on the cap, may have a function other than merely clamping the parts together in a position around the tube. I have previously described the clamping dies 19 and their set screws 20 as means for setting the fitting solidly upon the tubing, for the purpose of preventing any pressure from blowing the fitting off; and I shall describe

similar means in connection with the cap. It will be recognized, however, that the clamping means 28 and similar clamping means on the cap can be used not only for the purpose of simply closing the parts around the tubing, but also for the purpose of clamping the parts tightly enough on the tubing to prevent removal or relative movement.

10 The upper part of fitting F, when closed as shown in the drawings, constitutes a split cylindric extension portion which is provided with external threads 35. A cap C has an internally threaded bore 40 adapted to be screwed down over the cylindric externally threaded part 35. This cap C is also made in two halves, hinged together at 41 and held tightly together by the clamp 42 which is similar to the previously noted clamp 28.

15 Above the threaded bore 40 cap C has a tubing bore 43 provided with circumferential packing 44 and also with clamping dies 45 set up by set screws 46. By either the clamp 42 or set screws 46, or both, cap C, after having been closed around a length of tubing, may be clamped tightly thereto to make a fluid tight joint therewith. Consequently, when the parts are assembled, as shown in Figure 3, the fitting is securely mounted upon the tubing string and makes a fluid tight joint with it, and the length of tubing at the upper end of the tubing string is securely held in the cap C and with a fluid tight joint.

20 I apply at the top of tubing length 11a a swivel cap S, comprising a cap body 50 which takes the screw-threaded upper end of tubing length 11a, and an outlet pipe or tube 51 which is swivelly connected with body 50 by the swivel bearing 52. The outlet pipe 51 may be controlled by a valve 53 from which either a pipe or a flexible hose 54 may lead off to any desired point. The provision of this valve controlled outlet at the upper end of tubing length 11a makes it possible to relieve pressure controllably, if so desired, during the operations. Such a swivel cap, as I have indicated at S, may be applied to the tubing when it is initially installed, 25 so that it will always be in place ready for the operations to be described; and the valve controlled outlet from this swivel cap may thus be the outlet through which flow normally takes place.

30 Suppose now it is desired to adjust the tubing to a higher elevation than at the time it occupies. First the tubing is elevated so as to expose a collar 17 below its upper end. Whether or not there will be one or more 35 lengths of tubing 11a above this collar will depend entirely upon how high it is desired to raise the tubing. Next the fitting F is applied to that collar, all as will be understood from the drawings and the previous 40 descriptions. The position of the parts then

is the same as that shown in Figure 3 except that gate valve 21 is withdrawn to the left to open the tubing bore, and that the upper tubing length 11a is somewhat below the position shown in Figure 3 and is screw-threaded into the collar 17.

45 Next the cap C is applied to the lower fitting F and to the pipe, but occupying a lower position on the fitting than is illustrated in Figure 3. The pitch of threads 35 and 40 is the same as the pitch of the tubing threads 11b. Thus, when cap C has been applied and clamped to tubing length 11a, the tubing can then be unscrewed from collar 17 by the usual rotation, cap C rotating and threading 50 upwardly with the tubing length until the tubing is completely unscrewed from collar 17. Threads 35 and 40 are longer than the threads on the tubing, so that by continued unscrewing rotation of the tubing and cap 55 C the tubing length is carried up to a position such as that illustrated in Figure 3, with the cap C still in screw-threaded engagement on the fitting.

60 Thus, when the above described relative positions have been reached, gate valve 21 may then be moved to the right to close off the tubing bore between the upper end of collar 17 and the lower end of tubing length 11a. This having been done cap C may then 65 be removed from the tubing length and the tubing length lifted out of the fitting.

65 From the structures and operation that have now been described, it will be seen that the purposes of the screw-threads 35 and 40 100 by which the cap C is screw-threadedly mounted on fitting F, include the functions of making a fluid tight joint and also of guiding the upper tubing length when it is to be set up or unscrewed. The first function 105 of the screw-threaded joint is to provide a substantially fluid tight connection which allows such relative movement as is necessary in screwing and unscrewing the tubing length. Such a connection can, of course, 110 be formed in many different known manners, but a screw-threaded connection I deem to be preferable here because the screw-threads can easily be made to fit fairly tightly throughout their run and thus provide a 115 good fluid tight joint. The use of screw-threads at this point also has the advantage that, after a length 11a has been unscrewed from collar 17, that length may then be moved on up to the position shown in Figure 3, without any danger of moving the length up so high as to completely disconnect from fitting F before valve 21 is closed. And, furthermore, the screw-threaded connection also has the advantage of guiding the tubing length 120 11a as its threads 11b are entered in the collar threads.

125 If it is desired to lift the tubing through a vertical distance greater than the longest tubing stand which can be accommodated in the 130

derrick and hoisted at one time, a short nipple of tubing may then be connected up with collar 17 in the manner and by operations which will be described later. Having thus connected up a short tubing nipple, or even a whole length of tubing, with a cap S on the top, it will be apparent how further lengths of tubing may be lifted out of the well by repeating the operations hereinbefore described.

Whenever it is desired to add tubing lengths to the string, either for the purpose of lowering the string or for the purpose of attaching short pieces as above indicated, or short pieces for finally getting the whole string exactly to the desired adjustment, the operations are substantially the reverse of the operations before described. Fitting F having been applied to a collar 17 immediately below the uppermost end of the string, the uppermost length of tubing (which may be either a full length or a short nipple) may be removed as before described. Then an appropriate length of tubing, or a tubing stand of appropriate length, may be easily connected up with collar 17 which is clamped in fitting F. In this operation cap C will be applied to the length or stand near its lower end, and that cap C then will be screwed down on the fitting F. The length or stand being capped with a cap S, gate valve 21 may be open, and the lower end of the length or stand is thus screwed into collar 17. When this is done the fitting and cap may be removed from the tubing and the tubing lowered to the desired point. If exactly the desired tubing position is not reached in one such operation of removing or adding lengths of tubing, the operation may be repeated as many times as is necessary, with different lengths, until exactly the desired position is reached.

In Figures 2 and 6 I show a slight modification in my apparatus adapted to take flush joint tubing. Flush joint tubing, such as indicated at 11c, may be initially installed in the upper parts of the tubing string, the lower parts of which may be of ordinary collar-jointed tubing. By thus using flush joint tubing, a fluid tight joint may be made and maintained between the tubing and casing by utilizing a stuffing box fitting B; and this fitting may have an outlet 60 which may be valve controlled at 61. The only difference in fitting F, to accommodate flush joint tubing, is this: that the tubing bore 15 of fitting F runs throughout the fitting at uniform size instead of being enlarged as at 16 in Figure 3. Otherwise the structure and operation of fitting F, and of its cap C and all of the other parts, may be the same as hereinbefore described.

I have described a typical and illustrative embodiment of the invention in order that those skilled in the art may understand the invention itself by way of a complete and de-

tailed understanding of one illustrative form. The invention itself is not limited to such details as have been described, and they may be readily varied and modified, but rather the invention is only limited as is set forth in the following claims.

1. Flow control apparatus for wells embodying, in combination with a flow pipe in the well, a bipartite fitting adapted to be applied to and around the flow pipe at a joint therein, and adapted to make a fluid tight juncture with a flow pipe below such joint, said fitting having a vertical pipe-receiving bore and a valve movable transversely across said bore, a bipartite cap member adapted to be applied to and around the flow pipe above the fitting, said cap member engaging the fitting in a manner to form a fluid tight joint therewith and to allow screwing and unscrewing of the pipe joint, and means for clamping said cap to the pipe so that the cap rotates with the pipe as the latter is turned.

2. Flow control apparatus for wells embodying, in combination with a flow pipe in the well, a fitting adapted to be applied to and around the flow pipe at a joint therein, and adapted to make a fluid-tight juncture with a flow pipe below such joint, said fitting having a vertical pipe receiving bore and a valve movable transversely across said bore, a cap member adapted to be applied to and around the flow pipe above the fitting, said cap member having a screw-threaded engagement with the fitting, which screw-thread is of the same pitch as the screw-threaded pipe joint, there being more threads on the joint between the cap and fitting than on the pipe joint, and means to cap the uppermost end of the pipe.

3. A flow control apparatus for wells embodying, in combination with a flow pipe in the well, a bipartite fitting adapted to be applied to and around the flow pipe at a joint therein, and adapted to make a fluid-tight juncture with a flow pipe below such joint, said fitting having a vertical pipe receiving bore and a valve movable transversely across said bore, a bipartite cap member adapted to be applied to and around the flow pipe above the fitting, said cap member having a screw-threaded engagement with the fitting, which screw-thread is of the same pitch as the screw-threaded pipe joint, and there being more threads on the joint between the cap and fitting than on the pipe joint.

4. A flow control device adapted to be applied to a screw-threadedly jointed flow pipe, comprising a fitting having a vertical longitudinal bore through it adapted to receive a pipe, clamping means adapted to clamp said pipe in the fitting, a transversely operating valve in said fitting operating above the point of engagement of said clamping means with the pipe, said valve being adapted to be extended across the bore of the fitting, a cap adapted

to fit upon and around the pipe above the fitting, means for clamping said cap to the pipe, said cap being rotatable relative to said pipe, fitting and having a movable fluid-tight engagement with the fitting.

5. A flow control device adapted to be applied to a screw-threadedly jointed flow pipe, comprising a fitting having a vertical longitudinal bore through it adapted to receive a pipe, a clamping means adapted to clamp said pipe in the fitting, a transversely operating valve in the medial part of the fitting adapted to be extended across the bore, a cap adapted to fit upon and around the pipe above the fitting, said cap having a movable fluid-tight engagement with the fitting, means for clamping said cap to the pipe, both said fitting and cap being bipartite for placement about the pipe.

20. A flow control device adapted to be applied to a screw-threadedly jointed flow pipe, comprising a fitting having a vertical longitudinal bore through it adapted to receive a pipe, clamping means adapted to clamp said pipe in the fitting, a transversely operating valve in the medial part of the fitting adapted to be extended across the bore, a cap adapted to fit upon and around the pipe above the fitting, said cap having a screw-threaded engagement with the fitting and there being more threads on the joint between the cap and fitting than on the pipe joint.

25. A flow control device adapted to be applied to a screw-threadedly jointed flow pipe, comprising a fitting having a vertical longitudinal bore through it adapted to receive a pipe, clamping means adapted to clamp said pipe in the fitting, a transversely operating valve in the medial part of the fitting adapted to be extended across the bore, a cap adapted to fit upon and around the pipe above the fitting, said cap having a screw-threaded engagement with the fitting and there being more threads on the joint between the cap and fitting than on the pipe joint, both said fitting and cap being bipartite for placement about the pipe, and an outlet leading from the bore of said fitting below the valve.

30. A flow control device adapted to be applied to the flow pipe, comprising a fitting including two separable parts and means to clamp the parts together, the fitting having a longitudinal pipe receiving bore half in one part and half in the other, a transversely movable valve adapted to be extended across a medial part of the bore, and a pipe engaging cap comprising two parts and means for clamping them together, said cap also having a pipe receiving bore and having movable fluid-tight engagement with the fitting, means for clamping said cap to the pipe so that the cap rotates with the pipe as the latter is turned, and an outlet leading from the bore of said fitting below the valve.

35. A flow control device adapted to be ap-

plied to a pipe, comprising a fitting with a longitudinal pipe-receiving bore, said fitting composed of two parts meeting on a longitudinal plane diametrical of the bore, means for clamping the two parts of the fitting together, a valve in the fitting adapted to be extended across a medial part of the bore, a cap mounted on one end of the fitting at one end of the bore, said cap having a pipe receiving bore and being longitudinally movable relative to said fitting, means for clamping said cap to the pipe so that the cap rotates with the pipe as the latter is turned, and an outlet leading from the bore of said fitting below the valve.

40. A flow control device adapted to be applied to a pipe, comprising a fitting with a longitudinal pipe-receiving bore, said fitting composed of two parts meeting on a longitudinal plane diametrical of the bore, means for clamping the two parts of the fitting together, a valve in the fitting adapted to be extended across a medial part of the bore, a cap movably mounted on one end of the fitting at one end of the bore, said cap having a pipe receiving bore and being composed of two parts separable on a longitudinal plane diametrical of its bore, means for clamping the two parts of the cap together, means for clamping said cap to the pipe so that the cap rotates with the pipe as the latter is turned, and an outlet leading from the bore of said fitting below the valve.

45. A flow control device adapted to be applied to a pipe, comprising a fitting with a longitudinal pipe-receiving bore, said fitting composed of two parts meeting on a longitudinal plane diametrical of the bore, means for clamping the two parts of the fitting together, a valve in the fitting adapted to be extended across a medial part of the bore, a cap screw-threadedly mounted on one end of the fitting at one end of the bore, there being more threads on the joint between the cap and fitting than on the pipe joint, said cap having a pipe receiving bore and being composed of two parts separable on a longitudinal plane diametrical of its bore, means for clamping the two parts of the cap together, and an outlet leading from the bore of said fitting below the valve.

50. A flow control device adapted to be applied to a pipe, comprising a fitting having a vertical longitudinal pipe receiving bore therethrough, fluid-tight packing means in the fitting at the lower part of its bore, the fitting being composed of two separable halves meeting on a vertical plane diametrical of the bore, means for clamping the two halves together, a transversely movable valve member mounted in one of said halves and movable to and from a position extending across said bore above the fluid-tight packing, a cylindric externally threaded extension on the fitting concentric with and containing

- the upper part of the pipe receiving bore, a cap having an internal thread adapted to fit upon said screw-threaded extension of the fitting, there being more threads on the joint between the cap and fitting than on the pipe joint, said cap having a pipe-receiving bore coaxial with the pipe receiving bore of the fitting, means in the cap for forming a fluid tight joint in the pipe, and an outlet leading from the bore of said fitting below the valve.
18. A flow control device adapted to be applied to a pipe, comprising a fitting having a vertical longitudinal pipe receiving bore therethrough, fluid tight packing means in the fitting in the lower part of this bore, the fitting being composed of two separable halves meeting on a vertical plane diametrical of the bore, means for clamping the two halves together, a transversely movable valve member mounted in one of said halves and movable to and from a position extending across said bore above the fluid-tight packing, a cylindric externally threaded extension on the fitting concentric with and containing the upper part of the pipe receiving bore, a cap having a longitudinal vertical pipe receiving bore and having in its lower part an internally threaded bore concentric with its pipe receiving bore and adapted to engage the externally threaded extension of the fitting, there being more threads on the joint between the cap and fitting than on the pipe joint, said cap composed of two separable parts meeting on a vertical plane diametrical of its pipe-receiving bore, means for forming a fluid-tight joint between a pipe and the cap, and means for clamping the two halves of the cap together about the pipe.
40. In witness that I claim the foregoing I have hereunto subscribed my name this 26th day of November, 1929.
